UNITED STATES PATENT OFFICE.

JOHN J. HALLORAN, OF DALY CITY, CALIFORNIA.

PNEUMATIC CUSHION.

1,409,374.

Specification of Letters Patent. Patented Mar. 14, 1922.

Application filed January 25, 1921. Serial No. 439,779.

To all whom it may concern:

Be it known that I, JOHN J. HALLORAN, a citizen of the United States, and a resident of Daly City, county of San Mateo, and 5 State of California, have invented a new and useful Pneumatic Cushion, of which the following is a specification.

The present invention relates to improvements in cushions, and its object is to bring 10 about the cushioning effect by constructive features rather than by the qualities of the material used.

A further object is to produce a cushion that will require a minimum of material, 15 while the range of materials adapted to be used in its construction is practically limitless.

A further object is to provide a cushion that will adapt itself to a wide range of uses, 20 whether it be used as a single unit to ease the slamming of a door, or as a combination of many units designed to give resiliency to the running board of an automobile, a mat or the heel of a shoe.

25 I accomplish these objects by means of the mechanism illustrated in the accompanying drawing, in which:—

Figure 1 represents a plan view of my cushion; Figure 2 is a sectional view along 30 any diametrical line of Figure 1; Figure 3 shows a plurality of my cushions secured to the heel of a shoe; and Figure 4 a plurality of my cushions secured to the running board of an automobile.

35 Referring to the drawing more particularly, the principal parts of my cushion (1) are the base (2) and the cover (3). The base (2) may be made of any solid material, such as metal, wood, stone, glass, bone, hard 40 rubber, compressed composition and so on. In the illustration it is shown to be of circular shape, but I wish to point out that

this shape is not essential, in fact, the base may have practically any shape desired; it 45 may be oblong, square, triangular, cross-shaped, ring-shaped, etc. It is also shown in the drawing as being flat, but it may be made slightly curved, concave or convex, without departing from the spirit of my invention.

The base is provided with the rim (4) into which the rim of the cover (3) fits 50 snugly and from which the cover receives lateral support. The exact form of the rim is inessential, the principal feature being 55 that the cover firmly foots on the base and is prevented by the base from spreading laterally.

The cover (2) may be of any flexible material and is shown in the drawing as following, in its cross-section, the lines of the 60 arc of a circle. This, however, is only one outline among many possible ones, the principal feature being that it is arched and adapted to offer a certain lateral resistance to 65 vertical pressure. Its thickness may vary somewhat, but should bear a certain proportion to its other dimensions. It should be thick enough, not only to support its own weight, but also to offer some resistance to 70 vertical pressure and to return to its original position when the pressure is released.

I claim:

1. An anti-slipping device comprising a rigid base and an arched cover of flexible 75 material secured over it so as to form a rebounding air chamber with the same.

2. An anti-slipping device comprising a rigid base and a plurality of arched covers of flexible material secured over it so as to 80 form rebounding air chambers with the same.

JOHN J. HALLORAN.
